(57) **CLAIM**

The design for a media storage case, as shown and described.

DESCRIPTION

FIG. 1 is a front perspective view of one embodiment of the media storage case of the present invention;

FIG. 2 is a top view of the media storage case of FIG. 1; FIG. 3 is a left side view of the media storage case of FIG. 1;

FIG. 4 is a right side view of the media storage case of FIG. 1;

FIG. 5 is a bottom view of the media storage case of FIG. 1;

FIG. 6 is a rear view of the media storage case of FIG. 1; FIG. 7 is a front view of the media storage case of FIG. 1; FIG. 8 is a front perspective view of another embodiment of the media storage case of the present invention;

FIG. 9 is a top view of the media storage case of FIG. 8; FIG. 10 is a left side view of the media storage case of FIG. 8;

FIG. 11 is a right side view of the media storage case of FIG. 8;

FIG. 12 is bottom view of the media storage case of FIG. 8; FIG. 13 is a rear view of the media storage case of FIG. 8; and,

FIG. 14 is a front view of the media storage case of FIG. 8. The broken lines are for illustrative purposes only and form no part of the claimed design.
